UNITED STATES PATENT OFFICE.

AVEDISS B. HERALD; OF WASHINGTON, DISTRICT OF COLUMBIA.

DESIGN FOR A CLASP.

SPECIFICATION forming part of Design No. 32,357, dated March 20, 1900.

Application filed February 8, 1900. Serial No. 4,565. Term of patent 14 years.

To all whom it may concern:

Be it known that I, AVEDISS B. HERALD, a citizen of the United States, residing at Washington, in the District of Columbia, have invented and produced a new and original Design for Clasps, of which the following is a specification, reference being had to the accompanying drawings, forming part thereof, and in which—

Figure 1 is a face view, Fig. 2 a perspective view, and Fig. 3 an edge view, of a clasp, showing my new design.

As shown in the drawings, the leading or material feature of my design consists in the design forming the subject-matter of the accompanying illustrations.

As illustrated in the drawings, the clasp is shown as formed with the base arm or plate A and the overlying arm or plate B, which are arranged to converge from their united ends, where they are joined by a bow C. These arms A and B have their free ends turned

outwardly at A' and B' in the same direction and are corrugated from end to end, with the projecting portions of the corrugations of one arm entering the recessed portions of the corrugations of the other arm. In the opposite edges of the arms A and B are produced the pronounced notches A² and B², such notches A² and B² being coincident, as is shown in 25 30 the drawings.

Having described my invention, what I claim as new, and desire to secure by Letters Patent, is—

The design for a clasp, as herein shown and 35 described.

In testimony whereof I have signed my name to this specification in the presence of two subscribing witnesses.

AVEDISS B. HERALD.
